HYDROCARBON STORAGE TANK WITH
STRENGTHENED ROOF

Robert Maurice Mercier, Paris, France, assignor
to Societe pour le Renforcement des Domes de
Reservoirs a Petrole, Paris, France (societe a
responsabilite limite)

Application December 17, 1945, Serial No. 635,511
In France December 19, 1944

4 Claims. (Cl. 108--1)

1

It is known that hydrocarbons are generally stored in metallic tanks, having the shape of a vertical cylinder and provided with a roof in the shape of a calotte or a cone.

The wall and the metallic roof of these tanks are easily permeated by heat and the atmosphere prevailing inside the tank is heated by convection and radiation due to the fluctuations of temperature and irradiation of the outside atmosphere.

The fluctuations result in a sequence of expansions and contractions of the carburated air confined above the liquid fuel to cause an actual intake of air from the exterior and an expulsion of carburated air from the tank. To reduce this respiration caused by variations in temperature, it has been proposed to provide the tank with a breathing valve means in communication with the outside atmosphere when the internal pressure or vacuum exceed predetermined values fixed in relation to the resistance of the tanks.

The reduction of vapor loss from the tank thus depends on the pressures and vacuum for which the valve has been set.

Thus for example, a saving of about 30 per cent is observed if the vacuum is limited to 10 grams per square centimeter and the overpressure to 20 grams per square centimeter, and it would attain 90 per cent, if the tank could resist a pressure variation of from 80 to 100 grams per square centimeter.

Unfortunately, it is very difficult to construct tanks capable of resisting these high pressures under such working conditions, since the intricate feature is the assembling of the dome on the upper part of the cylindrical tank. As a matter of fact, the application of the gaseous pressure to the dome creates in the supporting angle iron assembly considerable compression stresses which are liable to cause said angle iron to collapse and to develop folds in the upper part of the cylindrical wall. This structural difficulty makes it difficult to construct new tanks gauged for 100 gram pressures and makes it practically impossible to modify existing tanks with heavier sheet metal to permit higher pressures.

It is known that by covering the outside of the dome with a layer of a nonconducting material, that the amplitude of variations in internal temperature and consequently the respiration will be reduced.

My invention relates to hydrocarbon storage tanks comprising a metallic body of upright cylindrical shape surmounted by a metallic dome assembled with the cylindrical body by means of a metal ring fitted inside said tank, which

2

ring is further provided with an outer concrete strengthening covering enabling the tank to withstand variations in internal pressure by far in excess of the values which are permitted in the usual metallic structures.

According to one embodiment of my invention, said strengthening consists of an annular concrete girder moulded around and against the outer surface of both the cylindrical body and 10 of the dome of said tank at the level of the assembling ring, said girder rigidly adhering to the cylindrical wall of the tank. The girder is rendered rigid with the assembling ring and with the cylindrical wall by a suitable means.

According to another embodiment, the said girder forms an integral part with a concrete cupola moulded onto the metallic dome and which comprises moreover radial trusses assembled on a central calotte. Said trusses may 20 be interconnected by metallic reinforcements secured to the outer wall of the dome.

In a third embodiment of my invention, the said concrete cupola, constructed to withstand vertical downward stresses, is covered after setting and hardening by a second concrete cupola of the same shape and adapted to withstand vertical downward stresses due to its weight.

My invention provides also particular means for rigidly uniting the concrete girder with the 30 metallic assembling ring and the vertical wall of the cylindrical body.

Furthermore, my invention provides means permitting the boarding or planking of the concrete girder to be constructed without the aid 35 of scaffolding. Means are also provided to increase the thermal insulation ensured by the concrete cupola.

Eventually, a safety device may be provided in the construction according to the invention to 40 automatically limit to predetermined values the variations in gaseous pressure prevailing inside the tank.

The above improvements are applicable to existing tanks or tanks to be constructed.

The improvements which will be described 45 hereinafter with reference to the appended drawings make the invention clearer and indicate the manner for realizing same.

Fig. 1 is a vertical section through a metallic 50 tank reinforced by means of an annular concrete girder.

Fig. 2 is a vertical section through a cupola covered metal tank reinforced by an annular girder integral with the concrete cupola.

Fig. 3 is a partial plan view of said cupola.

Fig. 4 is a detail view of the reinforcement girder.

Fig. 5 shows a modification applied to an existing tank.

Fig. 6 is a sectional view of the metallic assembling ring and shows a screw for rigidly connecting said ring with the vertical wall of the tank and with the circular concrete strengthening girder.

Fig. 7 shows in a partial cross-sectional view 10 a mold around the tank below the rim to form the concrete girder.

Fig. 8 is a cross-section of a double concrete cupola.

Fig. 9 is a partial cross-section of a cupola, similar to that of Fig. 8 and provided with a heat insulating means.

In the drawings, the tank is represented by its bottom 1, its cylindrical body 2, the roof frame with radial trusses 3 freely supporting the dome 4 built up with metal sheets assembled on the cylindrical wall by means of the assembling ring of rectangular cross-section 5. The dome has in its center the manhole 6.

Referring to Fig. 1, the upper part of the tank is encircled at the level where the dome is assembled with the cylindrical wall, by a reinforced concrete girder 7 whose section of approximately angle iron shape reinforces the angle iron assembling the dome on the cylindrical wall.

Said girder is provided with channels 8 separated from each other by a distance of about one meter permitting the rain water to flow off. A bitumen strip 9 prevents this water from penetrating between the concrete and the metal sheets of the dome in case it should accidentally happen that the concrete becomes detached from the sheet metal.

To construct the girder of reinforced concrete, it will be advantageous to previously subject the dome of the tank to an internal overpressure either by applying a gas under pressure approximately equal to the normal working pressure, or by completely filling the dome with water to subject the assembling angle iron and the adjacent sheets to a compression stress of the same order of magnitude as that resulting from pressures which the tank is to be exposed to.

In this manner the tank is secured by a hoop to the concrete crown to avoid the detachment from the metal sheet through the action of building stresses.

The securing of the crown to the tank is improved by providing carp-tail bolts 10, at approximately every 50 cm. of periphery for the rivets assembling the angle iron with the cylindrical wall. The concrete girder strengthens the head angle iron with which it is rigidly secured by the bolts 10 for adherence to the metal sheet and the hoop. Owing to its L-shaped section fitting over the assembling angle iron, the concrete girder effectively counteracts the tendency of the sheet to develop folds which may cause the assembly to collapse.

In the embodiment according to Figs. 2 and 3, the tank is provided with a circular concrete girder 11, having an angular section as in the embodiment of Fig. 1. Said girder is rigidly secured to the reinforced concrete trusses 12, 13, 14 etc. assembled on the reinforced concrete ring 15 in the center of the dome.

Between the trusses which support it, a reinforced concrete hourdis or rubble floor 16 is cast onto the sheet metal of the dome.

This assembly: circular girder, trusses and 75

hourdis ceiling constitutes a reinforced concrete cupola secured to the sheet metal and supported only by the vertical wall of the tank. Its adherence to said wall is further reinforced by the 5 hemispherical projections of rivet heads imbedded in the concrete during the casting of the latter.

The tank is thus covered with a composite dome consisting of an envelope made of thin and tight sheet metal which securely adheres to a heavy concrete cupola to provide the proper resistance to pressure and vacuum within the tank and to transmit vertical stresses to the wall of the tank through the rivet heads 17 (Fig. 4).

As in the case illustrated in Fig. 1, it will be advantageous to build up the girders and the cupola while submitting the metallic dome to a deformation through over-pressure.

The behaviour of the structure under the stresses is as follows:

When the tank is submitted to an internal over-pressure, the resistance opposed by the dome is the resultant of the resistance of the dome, of the weight of the concrete cupola and of the resistance of the concrete cupola. Under these conditions, the deformations of the sheet metal dome are limited to those of the concrete dome, and consequently the deformations of the head angle iron and of the annular reinforced concrete girder are the same. This avoids any separation between the reinforced concrete girder and the vertical cylindrical wall.

When the tank is submitted to an internal vacuum, the resistance of the dome is solely opposed by the reinforced concrete cupola wherein the sheet metal of the dome secured to the concrete fulfills the function of a reinforcement taking up tensile stresses whether in the case of the girder or in the case of a hourdis ceiling. The reaction of the latter and of the girders manifests itself through a tensile stress or expansion of the annular girder and through a vertical stress absorbed by the cylindrical wall of the tank.

The supplementary resistance which the concrete cupola confers to the sheet metal dome permits a very noticeable increase in the limits of respiration of the tank as compared with its original structure, and the operations of transformation and strengthening may be effected without the necessity of conducting caldron work or to penetrate the tank.

Moreover, in addition to its resisting action, the concrete hourdis layer acts as a heat insulating covering, reducing to a large extent the effect of irradiation and the fluctuations in pressure and vacuum caused thereby.

Due to the increase in weight of the tank resulting from the concrete cupola, it could be feared that when the tank is almost empty and the internal pressure forces the bottom to take a spherical shape, that the tank would rise above its foundations. To avoid this accident, a safety device is provided to reduce the overpressure to a rate compatible with the weight of the structure as soon as the pressure attains a predetermined value. This device consists of a tube 18 descending to a determined level above the bottom and provided at its upper part with a valve 19. It is obvious that as long as the base of the tube is immersed, that the respiration will take place through the high-gauge valve 20 and as soon as the base of said tube is uncovered, the respiration will take place through the low-gauge valve 19. A warning whistle combined

with the valve 19 is provided to indicate a maximum value of low-pressure which is not very economical.

As explained hereinbefore, the strength of the concrete cupola absorbs all of the stresses and consequently the original skeleton of the tank no longer fulfills this use.

If this method of building is applied to new tanks, it is therefore advantageous to replace the classical trusses of the dome with the type of reinforcement shown in Fig. 5.

This reinforcement to strengthen the structure consists of L- or T-irons shown at 21 in Fig. 5. Said irons are disposed like common rafters on the outside of the dome and welded onto the latter. Holes 22 provided in the vertical flange or web ensure a supplementary adherence of the concrete. The sectional rafters are imbedded in the concrete girders and not in the houddis ceiling.

When the natural adherence should be found deficient, the connection between the concrete of the reinforcement girder and the sheet metal of the tank may be strengthened in the manner shown in Fig. 6, by means of screws 23, made of medium hard and preferably "cement" steel. Said screws have a slightly conical shape and are screwed into the rivet holes. To put these screws in place, it suffices to cut the head 24 off the rivet 17 interconnecting the elements 2 and 5, to expel the rivet toward the interior of the tank and to forcibly drive the screw 23 into the hole thus uncovered. The conical shape of the screw 23 and the hardness of its metal enable said screw to cut therein its own thread in the elements to immobilize therein in a tight manner.

The screw thus fixed in the sheet metal and subsequently imbedded in the concrete ensures the rigid connection between the concrete and the sheet metal. Under normal conditions, the screws thus set in place are submitted or subjected to shearing stresses, but they may also be subjected to tensile stresses. The use of such screws does away with the necessity of penetrating into the interior of the tank, obviating the fixing of nuts therein or the piercing of holes. Moreover, there is no intricate use of taps nor is it necessary to employ heat for the electric welding of splinters or the like. This means even permits adhesive pieces to be secured to tanks in service or still containing their gaseous atmosphere, without there being any risk of injury.

Finally, the tapered shape of the screw permits the latter to be adjusted to holes of different diameters without affecting its tightness. Fig. 7 shows a means permitting the boarding to be mounted on the tank for the purpose of moulding the reinforcement girder. The bottom 25 of said boarding is carried at certain intervals by chair supports made of round bars of suitable diameter. The two legs 26 and 27 extending throughout the bottom 25 support the boarding through the medium of nuts 28 and 29.

The lateral side 30 of the boarding is held in place by wooden blocks which render it rigid with the bottom of the mould, and by round iron braces 32 fitted with nuts 33 which connect it rigidly with the tank.

The legs 26 and 27 as well as the braces 32 are suspended on the upper angle iron 5 of the tank by means of screws 23 driven vertically down into the sheet metal of the dome and into the next angle iron by the method mentioned with reference to Fig. 6.

After casting, setting and hardening of the concrete, the boarding is released by unscrewing the nuts 28, 29 and 33, while the chairs and bracings as well as their anchoring screws 23 remain imbedded in the structure.

This device avoids the use of poles, stays and scaffoldings resting on the ground. The cost of this conventional equipment is very high in case the work has to be done at a height of 10 to 15 meters.

Fig. 8 shows a manner of constructing the concrete cupola which permits increasing the reinforcement limits of the dome.

It is well known that the thickness and hence the strength of the concrete dome depend on the resistance of the sheet metal dome which serves as a base for the boarding and which is to withstand the weight of the concrete employed at the time of casting.

Practice has shown that the limit of thickness compatible with said resistance is of the order of 10 cm.

To obtain a reinforcement of larger thickness without it being necessary to brace the sheet metal dome of the tank by means of poles or internal skeletons, the method according to my invention should be carried out in the following manner:

Onto the wall 2 and the dome 4 are cast a girder 7 and a cupola 16 identical to those described before, but more particularly constructed to withstand vertical downward stresses. After the setting of this first concrete casting to the necessary strength, another girder 34 and another cupola, 16 are cast so as to adhere to the first concrete casting.

This second cupola may eventually be connected to the first cupola with iron bars, or, a reinforced concrete houddis ceiling may be provided with a proper resistance to overpressure and vacuum stresses which it will transmit to its own lateral girder and to the girder of the first casting with which it will be rigid, or a nonreinforced concrete casting may be provided which is opposed by its own weight accounting for the vertical downward stresses.

It is to be noted that the second nonreinforced concrete cupola may be employed to counteract the tendency causing the bottom of the tank to get out of shape under the action of overpressures, without trying to obtain any increased resistance of the dome to internal pressures.

Fig. 9 illustrates a means for improving the heat insulating qualities of concrete cupolas. It involves the application of a reinforced concrete coat 7, 16 of the type described with reference to Fig. 2. After this coat has hardened, tubular bricks are disposed on the surface of said coat. Said tubular bricks have triangular sections 36, 37 or trapezoidal sections 38, 39 or rectangular sections 40, 41. A layer of reinforced or nonreinforced concrete 42 is finally cast over said tubular bricks.

It will be understood that the tubular bricks retain air within their cavities in order to form a heat insulating screen between the external wall and the dome of the tank.

The use of the above mentioned coating permits this kind of heat insulating to be improved, since in those applications made to insulate the domes of tanks, the efficiency was reduced by reason of the feeble weight of the heat insulating material compatible with the resistance of sheet metal domes.

75 The device shown in Fig. 9 permits one there-

fore to combine: the reinforcement of the domes of tanks against the action of overpressure and vacuum, the heat insulating by means of tubular bricks containing air and finally the increased weight of the tank which is necessary to counteract the tendency of the bottom to get out of shape under the action of overpressure.

What I claim is:

1. A reservoir of the type used for storing hydrocarbons comprising a vertical cylindrical metallic wall, a metallic air-tight roof, a cover of reinforced concrete poured upon the external face of said metallic roof and adhering to said roof for reinforcing said roof against internal subpressures and superpressures, a reinforced concrete beam ring molded upon the exterior wall of the upper portion of said cylindrical metallic wall to which said reinforced concrete cover is connected, said ring being designed to absorb radial forces which are transmitted to it by the reinforced concrete cover under the influence of internal superpressures and subpressures and to secure the fixing of the concrete assembly upon the metallic cylindrical wall, solely by adherence of the concrete to the metal and by the surrounding 25 in concrete of the natural ruggedness of the metal and the heads of the rivets, the entire structure being calculated and carried out in such a way that the metallic wall of the roof no longer has to intervene particularly in the resistance of the 30 structure to the effects of internal subpressures and superpressures.

2. A metallic reservoir according to claim 1 in which the metallic roof comprises an exterior sustaining frame formed by girders secured upon the roof and whose vertical leg is perforated and roughened in such a manner that these girders serve to sustain the wall of sheet metal during the pouring of the concrete and then concurrently improve the adherence of the girders and the 40 concrete cover to the sheet metal roof.

3. A metallic reservoir according to claim 1 wherein supports are disposed in order to resist forces directed downwardly, and a second layer of concrete is poured adheringly upon the upper face of said concrete cover serving to set and support said second layer. 45

4. A reservoir of the type used for the storing of hydrocarbons comprising a vertical metallic cylindrical wall, a metallic airtight roof, a reinforced concrete cover upon the external face of said metallic roof adhering to said roof and reinforcing it against the effects of internal subpressures and superpressures, a reinforced concrete beam ring upon the exterior wall of the upper portion of said metallic cylindrical wall of said reservoir connected to said reinforced concrete cover, said ring beam absorbing radial forces transmitted to it by said reinforced concrete cover under the influence of internal superpressures and subpressures and securing the fixing of the concrete assembly upon said metallic cylindrical wall solely by adherence of concrete to the metal and surrounding in the concrete unevennesses and rivets so that the metallic wall of the roof does not intervene particularly in the resistance of the structure to the effects of internal subpressures and superpressures and steel elements located in the rivet holes projecting into the concrete to improve the assemblage of the latter upon the sheet plate and to improve the adherence.

MERCIER, ROBERT MAURICE.
